UNITED STATES PATENT OFFICE.

HORACE E. JOHNSON, OF BUSTLETON, PENNSYLVANIA.

ADJUSTABLE WINDOW-SCREEN AND FLYTRAP.

1,334,099.

Specification of Letters Patent. Patented Mar. 16, 1920.

Application filed October 21, 1916. Serial No. 127,009.

To all whom it may concern:

Be it known that I, HORACE E. JOHNSON, a citizen of the United States, residing at Bustleton, in the county of Philadelphia and 5 State of Pennsylvania, have invented new and useful Improvements in Adjustable Window-Screens and Flytraps, of which the following is a specification.

My invention relates to new and useful 10 improvements in adjustable window screens and fly traps, and has for its object to provide an exceedingly simple and effective device of this character comprising two members or frames hinged together along one 15 edge and provided with means for holding them in a closed position, each of said frames carrying a suitable foraminous material, such as wire screen, one of said screens having conical shaped depressions or passageway 20 ways projecting inwardly and located in a number of different positions, the other screen carrying suitable means to lure flies or other insects within the compartment between the two screens, from which place 25 they cannot escape and may be killed in any suitable manner after which they may be removed by opening the frames. One of said frames also carries a pair of oppositely disposed spring actuated adjustable slides, 30 said slides carrying a suitable foraminous material, such as wire screen, the inner edge of which is protected and strengthened by a metallic strip or shield.

With these ends in view, my invention 35 consists in the details of construction and combination of elements hereinafter set forth and then specifically designated by the claim.

In order that those skilled in the art to 40 which this invention appertains may understand how to make and use the same, I will describe its construction in detail, referring by numeral to the accompanying drawing forming a part of this application, in 45 which—

Figure 1, is a front elevation of an adjustable window screen and fly trap made in accordance with my improvement.

Fig. 2, is a similar view with one of the 50 frames partly open to more clearly illustrate the construction.

Fig. 3, is an enlarged side elevation of one form of conical passageway or inlet.

Fig. 4, is an end view thereof.

55 Fig. 5, is an enlarged view of the bait holding member.

Fig. 6, is an end view thereof.

Fig. 7, is an enlarged edge view of the window screen and fly trap.

Fig. 8, is an enlarged section on the line 60 8—8 of Fig. 1.

Fig. 9, is an enlarged elevation of a portion of the screen, the facing strips being removed from the stationary frame to clearly illustrate the internal construction; and 65

Fig. 10, is a fragmental sectional view on the line 10—10 of Fig. 9, the slide being shown in elevation.

In carrying out my invention as here embodied 2 represents the main or stationary 70 frame comprising a pair of parallel top and bottom rails 3 and 4 respectively, having top and bottom facing strips 5 and 6 secured thereto and joined together by side strips 7. Each of the rails 3 and 4 is provided with 75 a cutaway portion 8 at each end and the space between these cutaway portions is grooved longitudinally as indicated at 9. Each of the rails 3 and 4 between its inner face and the groove 9 is provided with a 80 slot 10 running longitudinally inward a desirable distance from the ends of the rails. In these grooves 9 in the rails 3 and 4 are slidably mounted the arms 11 formed integral with and projecting from the top and 85 bottom members 12 of the adjustable slides 13, said arms being of the same thickness as said members 12, but of less width, thereby producing shoulders 14 adapted to contact with the shoulders 15 formed by the 90 cutaway portions in the rails 3 and 4 to limit the inward movement of the adjustable slides 13.

Each of the arms 11 is provided with an elongated notch 16, thereby forming shoulders 95 17 and 18 which are adapted to contact with a pin 19 carried by the rails 3 and 4 and projecting across the grooves therein for further limiting the movements of the adjustable slides in either direction. The 100 balance of each of the adjustable slides comprises a side member 20 attached to the outer ends of the end members 12. All of the members of each adjustable slide have a suitable foraminous material 21, such as 105 wire screen secured thereto, the inner edge being protected and strengthened by a metallic strip 22 attached thereto.

When the adjustable slides are forced inward to decrease the size of the window 110 screen the wire screen 21 slides in the slots 10 and such inward movement compresses

the springs 23, one of which is mounted in each of the grooves 9 with the ends in engagement with the inner ends of the arms 11 and by the expansion of the springs 23 5 the adjustable slides are forced outward. The springs and arms of the adjustable slides are inclosed and held in position by the facing strips 5 and 6 and to these facing strips is secured the foraminous material 24 such as wire screening and the edges thereof may, if found desirable, be covered and protected by beading 25. To the inner face of this wire screen 24 and projecting inwardly therefrom are secured a number 10 of bait holding members 26 each preferably formed from foraminous material such as wire screening having the strands of wire projecting free at each end as indicated by 27, the free ends of the strands at one end 15 of the bait holding member being used to attach said bait holders to the wire screen while the free ends of the same strands at the opposite end of the bait holder are used for securing a lure thereto. 20 To the bottom rail 4 are attached suitable hinges 28, said hinges also being fastened to the swinging frame 29, the same being locked closed to the stationary frame 2 by a suitable hook 30 pivoted to the top 25 rail of the frame 2 and arranged to coact with a pin 31 carried by the swinging frame 29, said hook and pin being situated in depressions as plainly shown in Figs. 2 and 7. The swinging frame 29 comprises a top member 32, a bottom member 33 and side members 34, said side members carrying fillers 35 which fill the spaces between the screening of the adjustable slides and the side members of the swinging frame the 30 entire height of the window screen between the rails 3 and 4 and the space between the screens of the adjustable slides and the side members 7 is filled by similar fillers 36 carried by the side members 7 with which the fillers 35 align when the swinging frame is closed. These fillers may be formed with the members carrying the same or they may be separate pieces attached thereto. 35 To the swinging frame is secured the foraminous material 37 such as wire screen and this wire screen is provided with conical shaped inlets or passageways 38 which may be formed from the screen itself by stamping them from said wire screen, so 40 that they project inward and when the swinging frame is closed these inlets align with the bait holding members 26. These conical shaped inlets might also be made separate from the screen and produced 45 from foraminous material such as wire screen similar to the bait holders with the longitudinal strands of wire projecting beyond the annular wire strands, so as to leave free ends 39, whereby the separable inlets as 50 shown in Figs. 3 and 4 may be attached to

the screen 37 and surrounding openings in said screen.

From the foregoing description it will be seen that an exceedingly simple and effective adjustable screen is produced which 70 may be readily and quickly adjusted to fit different sized windows within certain limits, which when in position will also act as an insect trap, the insects being lured to the screen 37 by the bait within the compartment formed between the wire screens 75 24 and 37, and as they walk over the screen 37 in an endeavor to reach the bait, they will enter the inlets 38 and pass into the compartment between the wire screens. 80

Because of the shape of the inlets 38 it is very difficult for an insect such as a fly to again find the opening in the inlets, because of the smaller size of the inlet opening at the inner end. 85

After the insects are trapped they may be killed in any suitable manner as by throwing hot water over the screen, at which time the swinging frame 34 may be unlocked and opened for the removal of the 90 dead bodies.

Of course I do not wish to be limited to the exact details of construction as herein shown, as these may be varied within the limits of the appended claim without departing from the spirit of my invention. 95

Having thus fully described my invention, what I claim as new and useful, is—

A fly screen and trap comprising a main screen member having upper and lower and side rails, the upper of said rails being grooved and recessed, the side rails having cutaway portions, lateral extension screens having upper, lower and side rails, the upper rails cutaway for slidable reception in 100 the grooves in the upper rail of the main screen and for abutment with the wall of the recess formed therein, a hinged screen carried by the lower rail of the main screen having upper and lower and side rails and having openings formed therein to admit flies, the side rails cutaway to register with the cutaway portions in the side rails of the main frame whereby to receive the side 105 rails of the extension, the walls of the side rails being extended to form a closure between the extensions and the space between the main and hinged screen section, and screening sections secured by the free ends of the wires forming the same to the main 110 section for coöperating with the fly inlet opening in the hinged screen section to lure the flies thereinto. 115

In testimony whereof, I have hereunto affixed my signature in the presence of two 125 subscribing witnesses.
